Genus and species: *Dahlia×hybrida*.
Variety denomination: 'KLEDH11031'.

BACKGROUND OF THE NEW PLANT

The present invention comprises a new and distinct variety of *Dahlia*, botanically known as *Dahlia×hybrida*, and hereinafter referred to by the variety name 'KLEDH11031'. The new variety is the result of a cross conducted in 2007 in Stuttgart, Germany between female *Dahlia* plant 'DH 2006 0095' (unpatented) and male *Dahlia* plant 'DH 2006 0039' (unpatented). A single plant selection was subsequently chosen for further evaluation and asexual propagation.

The new variety was first asexually propagated by vegetative cuttings in May 2008 in Stuttgart, Germany and has been asexually reproduced repeatedly by terminal tip cuttings for 4 to 5 generations. The present invention has been found to retain its distinctive characteristics through successive asexual propagations.

Plant Breeder's Rights for this variety were applied for in the European Union on Jul. 8, 2011. 'KLEDH11031' has not been made publicly available more than one year prior to filing of this application.

SUMMARY OF THE INVENTION

The following are the most outstanding and distinguishing characteristics of this new variety when grown under normal horticultural practices in Stuttgart, Germany.

1. Large, red-purple flowers; and
2. A full, compact plant habit.

DESCRIPTION OF THE PHOTOGRAPHS

This new *Dahlia* plant is illustrated by the accompanying photograph which shows overall plant habit including blooms, buds, and foliage of the plant. The photograph is of a four month-old plant grown in a heated greenhouse and out-

side in Stuttgart, Germany in 2012. The colors shown are as true as can be reasonably obtained by conventional photographic procedures.

5 **DESCRIPTION OF THE NEW VARIETY**

The following detailed descriptions set forth the distinctive characteristics of 'KLEDH11031'. The data which define these characteristics were collected from asexual reproductions carried out in Stuttgart, Germany. The plant history was taken in May of 2012 on 3 month-old plants grown in 14 centimeter pots. The plants were grown in a heated greenhouse and pinched once at week 7. Color readings were taken under natural light. Color references are primarily to The 10 R.H.S. Colour Chart of The Royal Horticultural Society of London (R.H.S.) (2007 edition).

DESCRIPTION OF THE NEW PLANT

20 **Classification:**

Family.—Asteraceae.

Botanical name.—*Dahlia×hybrida*.

Common name.—*Dahlia*.

Denomination.—'KLEDH11031'.

25 **Parentage:**

Female parent.—'DH 2006 0095' (unpatented).

Male parent.—'DH 2006 0039' (unpatented).

30 **Growth:**

Form and habit.—Inverted triangle.

Growth habit.—Upright.

Branching habit.—Freely branching.

Height (from top of soil, including inflorescence).—25.0 cm to 35.0 cm.

Width (including inflorescence).—Approximately 25.0 cm.

Propagation.—Vegetative cuttings from tips.

Time to produce a finished flowering plant.—Approximately 9 weeks.

Time to initiate and develop roots.—8 to 21 days.

<i>Root description.</i> —Fine fibrous.	Length.—3.3 cm.
<i>Rooting habit.</i> —Fusiform.	<i>Width.</i> —1.8 cm.
Leaves:	<i>Apex.</i> —Emarginate.
<i>Leaf quantity per lateral stem.</i> —6 to 8.	<i>Base.</i> —Fused into a corolla tube.
<i>Type.</i> —Simple.	<i>Margin.</i> —Entire.
<i>Arrangement.</i> —Opposite.	<i>Texture (both upper and lower surfaces).</i> —Smooth.
<i>Shape.</i> —Ovate.	<i>Peduncle.</i> —Length: Approximately 5.0 cm. Diameter: 0.3 cm. Texture: Smooth. Color: RHS 143A.
<i>Apex.</i> —Acuminate.	Phyllaries:
<i>Base.</i> —Attenuate.	<i>Arrangement.</i> —Whorled.
<i>Margin.</i> —Serrate.	<i>Quantity.</i> —Approximately 24.
<i>Immature leaf.</i> —Color: Upper surface: RHS N137A. Lower surface: RHS 148C.	<i>Shape.</i> —Lanceolate.
<i>Mature leaf.</i> —Color: Upper surface: RHS N137A. Lower surface: RHS 139C.	<i>Color.</i> —Upper surface: RHS 143B. Lower surface: RHS 143C.
<i>Length.</i> —Approximately 11.0 cm.	<i>Length.</i> —1.6 cm.
<i>Width.</i> —Approximately 7.0 cm.	<i>Width.</i> —0.5 cm.
<i>Texture (both upper and lower surface).</i> —Leathery and rough.	<i>Apex.</i> —Acute.
<i>Venation pattern.</i> —Arcuate.	<i>Base.</i> —Obtuse.
<i>Petioles.</i> —Length: Approximately 3.5 cm. Diameter: 0.5 cm. Color: RHS 138B. Texture: Smooth.	<i>Margin.</i> —Entire.
Stems:	<i>Texture (both upper and lower surfaces).</i> —Smooth shiny.
<i>Total number of branches.</i> —5.	Reproductive organs:
<i>Length.</i> —Approximately 26.0 cm.	<i>Androecium.</i> —Location: Present on the disc floret. Stamens: Quantity: Approximately 30. Shape: Narrow elliptic. Color: RHS 20A. Filament length: 0.25 cm. Filament diameter: 0.05 cm. Anther: Shape: Narrow elliptic. Color: RHS 20A. Length: 0.3 cm. Diameter: 0.15 cm. Pollen: Color: RHS 16A. Amount: Moderate..
<i>Diameter.</i> —0.8 cm.	<i>Gynoecium.</i> —Location: Present at the base of ray and on the disc florets. Pistils: Number: 30. Length: 1.5 cm. Diameter: 0.3 cm. Stigma: Color: RHS 6A. Shape: Bipartite. Length: 0.3 cm. Diameter: 0.1 cm. Style: Color: RHS 13A. Length: 0.8 cm. Diameter: 0.1 cm. Shape: Filamentous.
<i>Internode length.</i> —Approximately 3.8 cm.	Fruit and seed set: Has not been observed.
<i>Color.</i> —RHS 141C.	Disease and insect resistance: Has not been observed.
<i>Texture.</i> —Smooth.	COMPARISON WITH PARENTAL AND COMMERCIAL VARIETIES
Inflorescence buds:	
<i>Shape.</i> —Round.	‘KLEDH11031’ differs from female parent ‘DH 2006 0095’ (unpatented) in that ‘KLEDH11031’ has red-purple flowers, whereas ‘DH 2006 0095’ has apricot-pink red eyed flowers.
<i>Length.</i> —1.2 cm.	‘KLEDH11031’ differs from male parent ‘DH 2006 0039’ (unpatented) in that ‘KLEDH11031’ has red-purple flowers, whereas ‘DH 2006 0039’ has cream-white yellow eyed flowers.
<i>Diameter.</i> —1.3 cm.	‘KLEDH11031’ is similar to the <i>Dahlia</i> plants of the HYPNOTICA series in terms of growth habit. ‘KLEDH11031’ differs from the <i>Dahlia</i> plants of the HYPNOTICA series in color pattern. Additionally, ‘KLEDH11031’ differs from the <i>Dahlia</i> plant of the HYPNOTICA series in that ‘KLEDH11031’ has semi-double flowers and more flowers per plant, whereas <i>Dahlia</i> plants of the HYPNOTICA series have double flowers and fewer flowers per plant than ‘KLEDH11031’.
<i>Color (at tight bud just before the ray florets unfold).</i> —RHS 144B at the apex and RHS 141B at the base.	We claim:
Inflorescence:	1. A new and distinct variety of <i>Dahlia</i> plant named ‘KLEDH11031’ as shown and described herein.
<i>Type.</i> —Terminal and composite.	
<i>Height.</i> —2.0 cm to 3.0 cm.	
<i>Depth.</i> —2.0 cm to 3.0 cm.	
<i>Blooming habit (flowering season).</i> —Spring to autumn.	
<i>Quantity of inflorescences per plant.</i> —Approximately 5.	
<i>Lastingness of the inflorescences on the plant.</i> —20 days.	
<i>Fragrance.</i> —Absent.	
<i>Inflorescence diameter.</i> —Approximately 8.5 cm.	
<i>Disc diameter.</i> —1.6 cm.	
Disc floret:	
<i>Quantity per inflorescence.</i> —30.	
<i>Shape.</i> —Tubular.	
<i>Tube color (closed).</i> —RHS 7A.	
<i>Tube color (mature).</i> —RHS 6A.	
<i>Length.</i> —0.8 cm.	
<i>Diameter (at apex).</i> —0.2 cm.	
<i>Apex.</i> —Five pointed.	
<i>Apex color.</i> —RHS 7A.	
<i>Base.</i> —Fused into a corolla tube.	
<i>Margin.</i> —Entire.	
Ray floret:	
<i>Quantity per inflorescence.</i> —Approximately 20.	
<i>Shape.</i> —Ovate.	
<i>Color.</i> —Upper surface: RHS 68B at the apex and RHS 53A at the base. Lower surface: RHS 76B at the apex and RHS 33B at the base.
